UNITED STATES PATENT OFFICE

HENRY J. HAMANN, OF TOLEDO, OHIO, ASSIGNOR TO LIBBEY-OWENS-FORD GLASS COMPANY, OF TOLEDO, OHIO, A CORPORATION OF OHIO

EDGING APPARATUS

Application filed May 13, 1932. Serial No. 611,090.

The present invention relates to glass edging apparatus and more particularly to novel means for maintaining the glass being edged in proper contact with the edging tool.

In the glass surfacing art, it is customary to use a continuous type of machine for the grinding and/or finishing of the edges of glass sheets. Broadly speaking, with such a machine, a number of spaced sheets of glass to be edged are vertically disposed in spaced relation relative to one another and passed substantially horizontally over and in contact with one or a plurality of surfacing elements whereby to first grind and then polish the edges of the sheets. It has been found, however, that with glass sheets of certain contours, difficulty is experienced in the moving of the sheets over the surfacing elements in that there is a tendency for the said sheets to tilt forwardly or rearwardly or otherwise get out of proper contacting relationship with said surfacing elements.

It is, therefore, an important object of this invention to provide novel and improved means for use upon edging machines of the above character which will function to maintain the glass sheets in proper operative relationship with respect to the surfacing elements.

Another important object of the invention is to provide means engaging the upper edges of the glass sheets which will serve to maintain the said sheets steadier and in a truer condition with respect to the surfacing elements than heretofore.

Other objects and advantages of the invention will become more apparent during the course of the following description when taken in connection with the accompanying drawing.

In the drawing forming a part of this application and wherein like numerals are employed to designate like parts throughout the same,

Fig. 1 is a side elevation of a portion of an edging machine with which the present invention is incorporated,

Fig. 2 is a sectional view taken substantially on line 2-2 of Fig. 1, and

Fig. 3 is a section taken substantially on line 3-3 of Fig. 2.

Referring now to the drawing, there is disclosed an edging machine including a supporting framework designated in its entirety by the numeral 5 and upon which is carried the horizontally arranged channel members 6 having positioned therein the supporting runways 7 longitudinally grooved as at 8. Also carried by the framework 5 are a plurality of grinding and/or polishing wheels 9 only one of which has been shown. However, each wheel is adapted to be rotated within a receptacle 10 containing a suitable abrasive material and is driven from a shaft 11 through suitable gearing (not shown). The upper portion of the surfacing wheel 9 is received within an opening between two adjacent channel members 6, and each wheel is provided with one or more grooves 12 around the periphery thereof. These grooves are in substantial horizontal alignment with the grooves 8 in runways 7. The particular construction of the surfacing wheel, together with the mounting and drive therefor, have not been illustrated specifically since they constitute no part of the present invention per se.

Mounted above the runways 7 is an endless sprocket chain 13 trained at each end of its loop about a sprocket 14, the upper run or flight of the chain being supported upon and sliding over a stationary supporting member or table 15. The upper edges of the side portions of the channel members 6 constitute guide rails along which pusher blocks 16 are adapted to be slid, these pusher blocks being suitably connected to and driven forwardly by the lower flight of the sprocket chain 13. The pusher blocks are preferably provided with a plurality of slots within which the rear vertical edges of the glass sheets 17 fit so that the said pusher blocks, therefore, serve to advance the glass sheet forwardly in the direction indicated by the arrow in Fig. 1. Slidably supported by the stationary member or table 15 is a guide member 18 engaging the forward edges of the glass sheets to guide the said sheets and maintain them properly spaced from one another.

The glass sheets 17 are shown as being rectangular and of greater height than width. During the surfacing operation, a plurality of sheets are first stood on edge upon one of the runways 7 at the forward end of the machine and are maintained in properly spaced relation by the guide member 18. The pusher block 16 is then moved to engage the rear edges of the sheets and to advance 10 the said sheets forwardly over successive surfacing wheels 9. As pointed out above, the surfacing wheels are provided with spaced peripheral grooves 12 extending around the periphery thereof, and the shape of these 15 grooves is such as to give the desired contour to the edges of the sheets being surfaced.

One of the difficulties ordinarily encountered in surfacing the edges of glass sheets upon a machine of the type described hereinabove, resides in the tendency of the sheets to 20 move forwardly in an ununiform or jerky fashion, and also in the tendency of the sheets to tip or tilt either forwardly or backwardly depending upon the profile of the glass during 25 the surfacing thereof and which naturally throws them out of proper operative relationship with respect to the surfacing wheel. The principal aim of the present invention therefore is to provide means for 30 overcoming this tendency of the glass sheets to tip, tilt or otherwise move out of proper position with respect to the surfacing wheels during the surfacing operation. To this end, there is provided new and novel means 35 engaging the upper edges of the glass sheets, which means offers a controllable amount of resistance to the forward movement of the glass sheets over the surfacing wheels.

In order to accomplish the above, there is 40 arranged opposite each surfacing wheel 9 a vertical standard 19 provided with a vertical slot 20 in which is slidably mounted a block 21. The block 21 and associated parts are supported by a cable 22 connected at one end 45 to the block and passing upwardly over a pulley 23 carried by standard 19. Secured to the opposite end of the cable is a counterweight 24 which serves to counterbalance the block 21 and the parts carried thereby. 50 Carried by the block 21 is a forwardly directed horizontal pin or trunnion 25 upon which is pivotally mounted a sleeve 26. Carried by or formed integral with this sleeve is a rod 27 upon which is slidable a weight 28 55 held in the desired adjusted position by a set screw 29. Also carried by or formed integral with the sleeve 26 and extending at substantially right angles to the rod 27 is an arm 30 terminating in a bearing portion 31 60 within which is mounted one end of the horizontal shaft 32. Rotatably mounted upon this shaft is a roller 33 preferably formed of rubber or a rubber composition material and being provided in its periphery with one 65 or a plurality of grooves 34 disposed in ver-

tical alignment with the grooves 12 in the respective surfacing wheel 9. Disposed between the shaft 32 and roller 33 is a bushing 35 which permits free rotation of the roller upon the shaft. 70

Loosely mounted upon the shaft 32 inwardly of roller 33 is a circular metal plate 36 provided with a series of round-headed projections or knobs 37 which engage the adjacent end of roller 33. Carried by the plate 36 is a fiber disc 38 and fixed upon the shaft inwardly of disc 38 is a collar 39 secured in place by a set screw or the like 40. 75

Also loosely mounted upon the shaft 32 outwardly of the roller 33 is a metal plate 41 similar to plate 36 and being likewise provided with a plurality of knobs or projections 42 which engage the outer end of the roller. Secured to the back of the plate 41 is a fiber disc 43 similar to disc 38. The outer end of shaft 32 is threaded as at 44, and threaded thereupon is a collar 45 held in place by a set screw 46. 80

From the above, it will be seen that the roller is adapted to freely rotate upon shaft 32 and that the metal plates 36 and 41 are caused to rotate therewith due to the provision of the knobs or studs 37 and 42 engaging opposite ends of said roller. Also, that by tightening up or loosening the collar 45, the roller can be moved longitudinally upon the shaft 32 so as to either increase or decrease the amount of friction between the fiber discs 38 and 43 and the respective collars 39 and 45. 90

During the surfacing of the lower edges of the glass sheets 17, the upper edges thereof are adapted to be received within the grooves 34 in the corresponding roller 33. Although composite or safety glass has been 105 illustrated in Fig. 2, yet it will be readily apparent that this machine may be used for grinding the edges of plate glass as well as other flat sheets or plates. 110

In operation, the glass sheets to be treated are first mounted upon one of the runways 7 at the forward end of the machine and placed in position for movement horizontally over the surfacing wheels. With the particular machine herein shown, five sheets of 115 glass 17 (Fig. 2) of similar shape and size are placed side by side and movable as a unit or a group simultaneously over the surfacing wheels. Upon actuation of the pusher device 16, the glass sheets will be carried forwardly and, as the lower edges thereof engage each successive surfacing wheel, the upper edges of the sheets will move beneath and in contact with the respective roller 33. Due 120 to the weight exerted by the roller upon the upper edges of the glass sheets, the said sheets will be held downwardly in contact with the surfacing wheel. In order to prevent either forward or backward tipping or tilting of 125 the glass sheets during the surfacing there- 130

of, and also to insure proper working relationship between the glass and surfacing wheel, the collar 45 is adjusted upon shaft 32 whereby to cause a binding action between 5 the fiber discs 38 and 43 (which rotate with metal plates 36 and 41), and the respective collars 39 and 45 which are fixed to the shaft. This will serve to exert a braking or retarding action upon the roller and will thereby 10 prevent said roller from freely rotating upon shaft 32. While in some cases it may be desirable to permit free rotation of the roller, yet it has been found by actual experience that with some sizes and shapes of glass 15 sheets, the braking or retarding of the roller in a manner to prevent free rotation thereof is of considerable importance, and that much more satisfactory edging results are obtained than where the roller is allowed to freely rotate. As set forth above, there is a tendency 20 for the glass sheets to tip or tilt either forwardly or backwardly during the surfacing thereof depending upon the profile of the glass, and it has been found that by preventing 25 free rotation of the roller so as to provide greater friction between the roller and glass sheets, the said sheets are held much steadier, are maintained in a truer condition, and the tendency thereof to tip or tilt is eliminated.

It is to be understood that the form of the invention herewith shown and described is to be taken as the preferred embodiment of the same, and that various changes in the 35 shape, size and arrangement of parts may be resorted to without departing from the spirit of the invention or the scope of the subjoined claims.

I claim:

40 1. In a machine for grinding an edge of a plate of glass, the combination of grinding means upon which the glass is partially supported on edge while being ground, means cooperating with the grinding means for 45 guidingly supporting said plate of glass during grinding thereof, a roller engaging the upper edge of the glass plate for maintaining it in a vertical position and in engagement with the grinding means, and means for preventing free rotation of said roller.

2. In a machine for grinding an edge of a plate of glass, the combination of grinding means upon which the glass is partially supported on edge while being ground, means 55 cooperating with the grinding means for guidingly supporting said plate of glass during grinding thereof, a roller engaging the upper edge of the glass plate for maintaining it in a vertical position and in engagement with the grinding means, and frictional means for retarding the rotation of said roller.

3. In a machine for grinding an edge of a plate of glass, the combination of grinding 60 means upon which the glass is partially

supported on edge while being ground, means cooperating with the grinding means for guidingly supporting said plate of glass during grinding thereof, a roller engaging the upper edge of the glass plate for maintaining it in a vertical position and in engagement with the grinding means, and means for applying a braking action to the roller to prevent free rotation thereof.

4. In a machine for grinding an edge of a plate of glass, the combination of grinding means upon which the glass is partially supported on edge while being ground, means cooperating with the grinding means for guidingly supporting said plate of glass during grinding thereof, a roller engaging the upper edge of the glass plate for maintaining it in a vertical position and in engagement with the grinding means, a shaft upon which said roller is rotatably mounted, and means carried by the shaft and engaging opposite ends of said roller for preventing the free rotation thereof.

5. In a machine for grinding an edge of a plate of glass, the combination of grinding means upon which the glass is partially supported on edge while being ground, means cooperating with the grinding means for guidingly supporting said plate of glass during grinding thereof, a roller engaging the upper edge of the glass plate for maintaining it in a vertical position and in engagement with the grinding means, a shaft upon which said roller is rotatably mounted, members carried by the shaft at opposite ends of the roller and rotatable with said roller, and means frictionally engaging said members for preventing free rotation of the roller.

6. In a machine for grinding an edge of a plate of glass, the combination of grinding means upon which the glass is partially supported on edge while being ground, means cooperating with the grinding means for guidingly supporting said plate of glass during grinding thereof, a roller engaging the upper edge of the glass plate for maintaining it in a vertical position and in engagement with the grinding means, a shaft upon which said roller is rotatably mounted, members carried by the shaft at opposite ends of the roller and rotatable with said roller, and additional members fixed to the shaft and frictionally engaging the first mentioned members for preventing free rotation of the roller.

7. In a machine for grinding an edge of a plate of glass, the combination of grinding means upon which the glass is partially supported on edge while being ground, means cooperating with the grinding means for guidingly supporting said plate of glass during grinding thereof, a roller engaging the upper edge of the glass plate for maintaining it in a vertical position and in engagement with the grinding means, a shaft upon

which said roller is rotatably mounted, members carried by the shaft at opposite ends of the roller and rotatable with said roller, fiber discs carried by said members, and means 5 frictionally engaging said fiber discs for preventing free rotation of the roller.

8. In a machine for grinding an edge of a plate of glass, the combination of grinding means upon which the glass is partially supported on edge while being ground, means 10 cooperating with the grinding means for guidingly supporting said plate of glass during grinding thereof, a roller engaging the upper edge of the glass plate for maintaining 15 it in a vertical position and in engagement with the grinding means, a shaft upon which said roller is rotatably mounted, members carried by the shaft at opposite ends of the roller and rotatable with said roller, fiber 20 discs carried by said members, and additional members fixed to the shaft and frictionally engaging the fiber discs for preventing free rotation of the roller.

Signed at Toledo, in the county of Lucas
25 and State of Ohio, this 9th day of May 1932.
